UNITED STATES PATENT OFFICE.

LOUIS ALEXANDRE CADORET, OF PAWTUCKET, RHODE ISLAND.

COMBINED SILK TUBE AND SPINDLE RETAINER.

Application filed April 16, 1923. Serial No. 632,443.

To all whom it may concern:

Be it known that I, LOUIS A. CADORET, a citizen of the United States, residing at Pawtucket, in the county of Providence and 5 State of Rhode Island, have invented certain new and useful Improvements in Combined Silk Tubes and Spindle Retainers; and I do declare the following to be a full, clear, and exact description of the invention, such as will enable others skilled in 10 the art to which it appertains to make and use the same.

This invention relates broadly to improvements on shuttles, but it has more specific 15 reference to an improved retainer which is to be permanently secured in the shuttle, the same being such as to enable the usual pivoted spindle to be entirely dispensed with.

20 The principal object of the invention is to provide a simple and inexpensive retainer constructed from a single length of wire and so bent as to enable it to serve a double function, that is, to hold the spindle in 25 operative position and to simultaneously grip and retain a silk tube on the spindle.

Another object of the invention is to provide a retainer of the above type which is such in construction that it can be employed 30 for directly engaging and holding in place a conventional type of bobbin.

35 A further object of the invention is to utilize unique means for securing the retainer in the shuttle without requiring extensive altering or cutting of the same.

Other objects and advantages of the invention will be apparent as the description goes on.

In the accompanying drawings forming a 40 part of this specification and in which like numerals are employed to designate like parts throughout the same:

Figure 1 is a top plan view of one end 45 of a conventional type of shuttle showing the improved combination retainer associated therewith.

Figure 2 is a bottom plan view of Fig. 1 disclosing more clearly the method of securing the retainer to the shuttle.

50 Figure 3 is a side elevation of the same end of the shuttle with portions broken away and shown in section to disclose the construction more clearly.

55 Figures 4 and 5 are transverse vertical sections taken on the lines 4-4 and 5-5 respectively of Fig. 3.

Figure 6 is a detail perspective view of the improved retainer and spreader plate.

Figure 7 is a view like Fig. 1 showing the manner in which the retainer co-acts 60 with the ordinary type of bobbin.

In the drawings, the letter S designates a conventional form of shuttle, A designates a removable tapered spindle having a head H at its inner end, and T designates a conventional type of circumferentially grooved silk tube which is fitted onto the spindle. At this time, it may also be conveniently mentioned that the letter B (Fig. 7) designates a conventional type of bobbin with 70 which one embodiment of the improved retainer is capable of co-action.

The improved retainer is generally designated by the reference character 1 and although it may be constructed otherwise, it 75 is preferably formed from a single length of wire which is bent between its ends as at 2 to provide a pair of spaced parallel attaching arms 3. Intermediate their ends, the arms are bent down as at 4 and their 80 free extremities are bent at right angles to extend upwardly. These upbent portions constitute gripping jaws 5 adapted to grip the silk tube and spindle in the manner shown. In order to insure an effective grip, 85 the central portions are bowed outwardly intermediate their ends so as to conform to the surfaces which they grip. Also, the extremities of the jaws are flared as indicated at 6 to facilitate insertion of the spindle 90 and tube.

As before indicated, it is desirable to so design the retainer as to enable it to be secured to a conventional type of shuttle without requiring extensive alterations. It 95 is obvious that with the type of retainer described, it is only necessary to form a relatively narrow and longitudinally elongated recess 7 in the bottom of the shuttle adjacent the left-hand end and to form undercutts in the bottom of this recess as indicated at 8. It is obvious that the recess 7 is sufficiently wide to accommodate the attaching portion of the retainer, but the undercut portion 8 of the recess is of a greater 100 width than the distance between the attaching arms 3. Inasmuch as the inherent resiliency of the wire causes the attaching arms and gripping jaws of the retainer to approach one another, it is necessary in order 105 to hold the arms in the undercut part of the recess to make use of a small flat plate 110

9 which may be conveniently termed a spreader. As seen in Fig. 6, this plate is positioned between the attaching arms with its curved end 10 engaged with the correspondingly bent portion 2 of the retainer. By placing the plate 9 between the arms, the latter are spread in the undercut part of the recess. To act in conjunction with this plate, a retaining bolt 10 is employed and the plate is formed with an opening to accommodate the head of the bolt and the shuttle is provided with a vertical bore to permit passage of the bolt therethrough. If desired, the upper end of the bore of the shuttle may be shaped as shown to accommodate the nut on the bolt and to prevent accidental rotation thereof.

It is obvious that the type of retainer just described is comparatively small and is especially adapted for use in connection with the metal spindle and silk tube shown in Fig. 3. It is further obvious that when the retainer is in place, the gripping jaws are spaced from the solid portion P of the shuttle so as to accommodate the head H of the spindle. In use, it will be seen that the improved retainer will serve a double function, that is, to hold the spindle in operative position, and to simultaneously grip and retain a silk tube or similar thread-carrier on the spindle.

As before intimated, the type of retainer herein described is also capable of being used in connection with an ordinary type of cotton holding bobbin B as seen in Fig. 7. By directing attention to this figure, it will be seen that it is only necessary to enlarge the jaws of retainer to accommodate the bobbin. The curved portions 5^a of the enlarged gripping jaws are received in the usual groove G in the head of the bobbin and an effective grip is assured. The free extremities 6^a are also spaced a greater dis-

tance apart than in the type of retainer first described.

The foregoing description when considered in connection with the drawings will doubtless be sufficient to enable persons skilled in this art to obtain a clear understanding of the invention and the advantages derived therefrom. It is therefore unnecessary to give a more lengthy and detailed description of the invention.

In the claim of this application, it is intended that the retainer clip cover the use in connection either with the silk tube and spindle or with a conventional type of bobbin. Therefore, these parts are to be construed broadly as thread-holding means or as a core therefor.

I claim:

In combination, a shuttle having a recess formed in its bottom adjacent one end, the side walls of said recess being undercut, combined means in said shuttle for holding a spindle in operative position in the latter and for simultaneously holding a thread-core on the spindle, said means being formed from a single length of wire bent between its ends to provide spaced parallel attaching arms, the outer ends of said arms being bent upwardly at substantial right angles to provide a pair of spaced gripping jaws which are bowed outwardly intermediate their ends to conform to portions of an object to be gripped thereby, the free extremities of the jaws being flared outwardly in opposite directions to facilitate insertion of the object between them, and a spreader plate arranged between said arms for forcing them into the undercut portion of the aforesaid recess for maintaining said means in place.

In testimony whereof I have hereunto affixed my signature.

LOUIS ALEXANDRE CADORET.
